UNITED STATES PATENT OFFICE.

GEORGE B. HOWELL, OF PHILADELPHIA, PENNSYLVANIA.

FLEXIBLE SEALING-JOINT FOR FRUIT-JARS.

SPECIFICATION forming part of Letters Patent No. 509,223, dated November 21, 1893.

Application filed March 8, 1893. Serial No. 465,076. (No model.)

To all whom it may concern:

Be it known that I, GEORGE B. HOWELL, a citizen of the United States, residing at Philadelphia, in the county of Philadelphia and 5 State of Pennsylvania, have invented certain new and useful Improvements in Flexible Sealing-Joints for Fruit-Jars, Bottle-Stoppers, &c.; and I do hereby declare the following to be a full, clear, and exact description 10 of the invention, such as will enable others skilled in the art to which it appertains to make and use the same.

This invention relates to joints for connecting the caps of fruit jars, bottle stoppers and 15 other tubular structures.

One object is to provide a joint which shall be tight, but not rigid, so that when applied to glass, earthenware, or other breakable structures, the connections may yield sufficiently to 20 prevent breakage and at the same time secure a perfectly air and water tight joint.

Another object is to dispense with the use of fastening devices for securing the parts which form the joint, so as to prevent dis- 25 connection thereof in use, and to provide a self-securing or self-locking joint.

The invention will first be described in connection with the accompanying drawings and then pointed out in the claims at the end of 30 this description.

Referring to the drawings by letters of reference, Figure 1 represents a vertical sectional elevation of a fruit jar top with attached sealing ring and detached cap. Fig. 2 is a similar 35 view showing the cap and ring in position upon the top of the jar or bottle neck and forming a sealed joint. Fig. 3 is a vertical sectional elevation illustrating a modification of the improvements showing the same adapted for connecting tubular sections of piping. Figs. 4 and 40 5 are side or edge views of the elastic packing ring detached, showing the same expanded in Fig. 4, and contracted in Fig. 5, as it appears under compression when affixed to the tubular 45 bottle neck or similar connection; and Fig. 6 is a detail sectional view of a further modification.

Similar letters of reference are used to denote similar parts in each of the several views. 50 A, may denote a fruit jar top or the neck of a bottle or other tubular fixture having a terminal exterior circumferential flange a.

B, denotes an elastic packing ring of soft pliable resilient material such as rubber, cork or the like, and which is adapted to fit 55 over the mouth of the jar or the end of the tubular connection so as to protect the latter from contact with the metal cap or coupling piece, when the latter is pressed down over the same as shown in Fig. 2.

The ring C, preferably consists of molded rubber and is formed with an interior circular projection or flange b, and a depending outwardly beveled main portion b', for engagement with the circular depending flange 65 c, of the cap or coupling piece so that when the latter is placed over the ring and top of the bottle neck and pressed downward thereon the enlarged portion b' of the ring will be pressed inwardly and expanded against the 70 sides of the tubular fixture or bottle neck, as indicated in Fig. 2, thereby compressing the ring about the circumferential flange a, so as to firmly connect the parts and form a sealed joint. By thus expanding the ring against 75 the exterior of the tubular fixture so as to overlie and embrace the flange a, the parts are firmly secured in position without other fastening means, the ring thus fulfilling the double purpose of sealing the joint or mouth 80 of the bottle neck and also holding the parts in the desired position, without the necessity of using other fastening devices such as are ordinarily employed in devices of this character.

In Fig. 3 is shown a cap or coupling piece C', which is formed with a screw-threaded cylindrical projection or flange c', for attachment to a corresponding tubular connection, when the joint is to be applied in connecting 90 piping or other tubular structures. In this instance the part A', may represent a hollow projection or socket forming a part of an earthen or metallic fixture to which a pipe is to be attached by the nipple or coupling piece 95 C'. The connection in this instance is precisely the same as described with reference to Figs. 1 and 2, except that instead of a closed cap or cover C, the part C', is provided with a central circular opening and a surrounding screw-threaded flange or projection for the attachment of an adjacent tubular section.

I desire it to be understood that although

my invention is designed particularly for effecting a yielding or flexible connection between tubular fixtures of glass or earthenware and a metallic cap or coupling section so as to provide a tight but yielding joint which will prevent breakage which frequently results in practice by the use of a rigid joint, yet I do not desire to be limited in the application of the invention to earthen or glass fixtures as it is obvious that the improvement may be applied to effect a connection in which all the parts are composed entirely of metal, save the interposed elastic packing ring.

15 In Fig. 6, which illustrates in full and dotted lines respectively, the closed cap or cover and open coupling piece with screw-threaded projection, the depending peripheral flange is provided with an interior annular shoulder 20 or projection c^2 , which, when the parts are connected, will pass underneath the inclined or beveled edge b' , of the ring as shown, and form a lock joint, by which the parts are permanently connected. This feature is particularly desirable in connecting fixed sections of piping or other tubular structures wherein a detachable joint is not desired.

To avoid confusion in the use of terms and alternative expressions in the appended 30 claims it may be stated that the term cap as employed in the claims with reference to the tubular fixture to which it is adapted to be applied, is intended to designate either the closed fruit jar cover or the coupling piece 35 with circular opening and screw threaded projection, while the term fixture may apply to either the fruit jar, bottle mouth, fruit can or other tubular part to which the cap or coupling piece is to be attached, the function 40 of these parts being the same when applied to either use.

In sealing fruit jars or cans it may be desirable to dispense with the lock-joint connection shown in Fig. 6, and to provide an 45 ordinary stopper fastener as an additional security when the device is used without said locking shoulder.

Having thus fully described my invention, what I claim as new, and desire to secure by 50 Letters Patent of the United States, is—

1. A closure for fruit jars &c., comprising an expandible ring arranged over the mouth of the jar and provided with an enlarged de-

pended outwardly beveled or inclined portion overhanging an exterior annular lip or 55 flange on the jar mouth and a cap or cover fitting over said ring and compressing said enlarged portion about said annular lip so as to seal the joint and secure the several parts together without other fastening means, sub- 60 stantially as described.

2. In combination with the tubular fixture having the exterior annular flange or lip, the angular elastic ring fitting thereon and having the portion thereof overhanging said lip 65 enlarged and beveled or inclined outwardly from the fixture, and the detachable cap fitting over said ring and compressing the expanded portion thereof about said annular lip 70 so as to seal the joint between the parts and securely connect the same without other fastening means, substantially as described.

3. In a closure for fruit jars, &c., the combination with the jar having the annular exterior lip or flange encircling the mouth thereof, 75 of the angular elastic ring formed with an enlarged expandible depending rim overhanging and embracing said lip and a cap adapted to fit over said ring and compress the rim thereof against the neck of the jar so as to 80 firmly connect the parts and seal the joint between the same, substantially as described.

4. In a closure for fruit jars, &c., the combination with the tubular fixture having the exterior annular lip encircling the mouth 85 thereof, of the angular elastic ring having an enlarged depending rim fitting over and embracing said lip and the detachable cap fitting over and embracing said ring and adapted to compress and lock the same 90 to said lip, substantially as described.

5. In combination with the tubular fixture having the exterior annular lip or terminal flange, the elastic ring having the right angled outwardly beveled and enlarged compressible portion overhanging and embracing said lip, and the cap having the interior annular shoulder adapted to abut against the depending edge of said rim and lock the parts together, substantially as described. 95

In testimony whereof I affix my signature in presence of two witnesses.

GEO. B. HOWELL.
